UNITED STATES PATENT OFFICE.

FREDERICK PURDY, OF CHICAGO, ILLINOIS.

TIME-STAMP.

No. 901,469.

Specification of Letters Patent.

Patented Oct. 20, 1908.

Application filed October 24, 1904. Serial No. 229,869.

To all whom it may concern:
Be it known that I, FREDERICK PURDY, a citizen of the United States, residing at Chicago, in the county of Cook and State of Illinois, have invented new and useful Improvements in Time-Stamp, of which the following is a full, clear, concise, and exact description, reference being had to the accompanying drawing, forming a part of this specification.

My invention relates to time stamps and automatic numbering devices.

In many places, such as record rooms, where documents are recorded, it is necessary to indorse thereon the exact time when the document is filed for record, and also to numerically number the documents so filed.

One of the objects of my invention is the combining in a single compact stamp, mechanism for printing time and an automatic numbering device.

For the purpose of revealing my invention, I have worked out one form thereof, which is illustrated in the accompanying drawings, in which the same reference characters are used to designate like parts in the several figures.

The other novel features of my invention will appear from the following description of my invention as illustrated in said drawings, and particularly pointed out in the appended claims.

In the drawings, Figure 1 is a front sectional elevation of my invention; Fig. 2 is a view of the impression adapted to be made thereby; Fig. 3 is a sectional view taken on the line 3-3 of Fig. 1; Fig. 4 is a sectional view on the line 4-4 of Fig. 1; Fig. 5 is a view on the line 5-5 of Fig. 1; Fig. 6 is a sectional view taken on the broken line 6-6 of Fig. 1; Fig. 7 is a sectional view on the line 7-7 of Fig. 1; Fig. 8 is the same as Fig. 7, showing the impression mechanism in engagement with the surface to be impressed; and, Fig. 9 is a sectional view on the line 9-9 of Fig. 1.

Referring to the drawings by reference characters, a suitable supporting frame is provided, said frame having legs or gage parts 1, 1, adapted to engage the surface to be stamped and adjust the impression mechanism relative to said surface. Said casing has side walls 2, 2, preferably turned down therefrom and adapted to inclose the impression mechanism. Said side walls extend between the end pieces 3, 3, which sup-

port a table 4, said end pieces and table constituting the supporting frame for the device. Mounted upon the table 4 is any suitable clock train or horologic motor mechanism (not shown), having a winding stem 5, and being adapted to continuously drive the impression mechanism to be hereafter described, by means of the shaft or rod 6, and pinion 7. A suitable casing or cover 8 for the motor mechanism is adapted to rest upon the table 4.

A central post or rod 9 is adapted to reciprocate within a suitable bearing or aperture 10 in the table 4, said rod carrying a downwardly extending portion 11, said portion being offset to accommodate the relative sizes of the printing mechanism and numbering device, as shown in Fig. 1. A suitable supporting plate 12 is provided, said mechanisms being pivoted to the extended portion 11 of the rod 9, and the downwardly extending end of the supporting plate 12. Carried by the supporting plate 12 is a suitable handle 13 for actuating the impression mechanisms, said handle being adapted to move the rod 9, and plate 12, when an impression is made. A coiled spring 14 is disposed about the rod 9, between the table 4 and the supporting plate 12, and is adapted to retain the printing mechanism in normal position, the handle 13 being depressed against the power of the spring 14 when an impression is made.

A suitable shaft 15 is journaled between one of the downwardly extending ends of the supporting plate 12, and the extended end of the rod 9, said shaft carrying a plurality of type wheels.

In time stamps having a plurality of type wheels for printing time, it is desirable that the wheels remain stationary and in position for making an impression, and that said wheels be moved quickly and intermittently to vary the character of the impression adapted to be made thereby, in order to have the said wheels, at all times in position for making the proper impression, and that said wheels may remain stationary while an impression is being made.

To accomplish the above result, I preferably mount the type wheels loosely upon the shaft 15, said wheels being adapted to be moved quickly and intermittently to bring the proper characters or symbols carried upon the peripheries of the wheels in alignment for making an impression. The means

employed for accomplishing this relative intermittent movement of the type wheels, is a system of cams and ratchet wheels attached to said type wheels, said ratchet wheels being moved by a series of pawls, said pawls being actuated by a second series of pawls adapted to ride upon and follow the contour of said cams. A stationary shaft 16 is pivoted between the extended end 10 11 of the rod 9, and the supporting plate 12, said stationary shaft being adapted to support said ratchet actuating and cam riding pawls, said stationary shaft also supporting, one end of a narrow plate or bar 17, the 15 other end of said bar being supported by the downwardly extending end of the post 9, said bar being adapted to support a plurality of small coiled springs for holding said ratchet and cam pawls in engagement with 20 their respective ratchet and cam wheels.

The symbols carried upon the peripheries of the loosely mounted type wheels are preferably arranged thereon in the following order; the type wheel 18 carries the numerals 25 1, 2, 3, 4, 5, 6, 7, 8, 9, 0, the type wheel 19 carries the numerals 1, 2, 3, 4, 5, 0, 1, 2, 3, 4, 5, 0, the type wheel 20 carries the numerals 1, 2, 3, 4, 5, 6, 7, 8, 9, 10, 11, 12, the type 30 wheel 21 carries six A. M. characters, arranged consecutively, and six P. M. characters, arranged consecutively. The type wheel 22 carries the numerals 1, 2, 3, 4/5, 6, 7, 8, 9, 0, and the type wheel 23 carries the following blank spaces and numerals, blank 1, 2, 3, 35 blank 1, 2, 3, blank 1, 2, 3.

The type wheel 18 is adapted to print the units column of the minutes and the type wheel 19 is adapted to print the tens column of the minutes. It will be seen, therefore, 40 that when the type wheel 18 makes one revolution the type wheel 19 should be moved one notch or to bring the next character upon said wheel into printing position. The type wheel 20 is adapted to print the hour, consequently when the type wheel 19 has made a 45 half revolution the type wheel 20 should be turned to bring the next character thereon into printing position. The type wheel 21 which carries the indications "A. M." and 50 "P. M." is moved one notch or to bring the next character thereon into printing position, when the type wheel 19 has moved one revolution, thus bringing one of the indications "A. M." or one of the indications 55 "P. M." into printing position every two hours. The type wheel 22 is adapted to print the units column of the day of the month, the said wheel being adapted to move to bring the next character thereon into 60 printing position when the wheel 21 has made one revolution, and the wheel 23 which prints the tens column of the day of the month is moved to bring the next character thereon into printing position when the 65 wheel 22 is moved one revolution.

The shaft 15 is driven continuously by the motor mechanism by means of the pinion 7, the idle pinion 24 carried by the stationary shaft 16 and the pinion 25 carried by the shaft 15, as shown in Fig. 3. Pivoted to the 70 pinion 25 and adapted to rotate with said pinion is a cam wheel 26 shown in Fig. 4. A cam riding finger or pawl 27, is pivoted to the stationary shaft 16, said pawl preferably having two arms or members adapted to engage the cam wheel 26 upon diametrically opposite sides thereof and to oscillate thereon as the cam wheel 26 is rotated. An escapement wheel 28, shown in Fig. 6, is carried by the shaft 15, said escapement wheel 80 having a hollow interior arranged concentrically with the shaft 15, and preferably having a small flat coiled spring 29 disposed within said hollow interior, one end of said spring being attached to the escapement wheel 28, and the other end thereof being attached to the shaft 15. A U-shaped escapement lever 30 is adapted to engage the periphery of the escapement wheel 28, the arms of the lever preferably engaging the 90 wheel on diametrically opposite sides thereof, said escapement lever being pivoted by means of pins 31 to the cam pawl 27, the movement of the escapement lever 30 being controlled by the oscillations of the cam pawl 27. The cam 32 and the type wheel 18 are pivoted to the escapement wheel 28.

A cam riding pawl 33 pivoted to the stationary shaft 16 is adapted to follow the contour of the cam 32, said pawl being held in engagement therewith by the small coiled spring 34 preferably held in position by the plate or rod 17. Preferably formed integral with the cam pawl 33 is a strip 35 extending longitudinally with the shaft 15, the free end 105 of said strip being pivoted to said shaft, as shown in Fig. 9. The strip 35 carries a small-projecting lug or finger 36. Pivoted to the shaft 15 is a plate 37 having a slot formed in the free end thereof engaging a pin secured to the projection 36 carried by the rod or bar 35. Pivoted to the plate 37 is a ratchet actuating pawl 38 held in engagement therewith by a small spring, and adapted to engage the periphery of the 115 ratchet wheel 39, said ratchet wheel being pivoted to and adapted to rotate the type wheel 19, as shown in Fig. 1.

The operation of so much of the printing mechanism as has been described, is as follows: The shaft 15 is rotated continuously by pinions 7, 24, and 25. The escapement wheel 28 is held from rotation by the prongs of the escapement lever 30. As the shaft 15 is rotated power is stored in the small coiled 125 spring 29. As the cam wheel 26 oscillates the cam riding pawl 27, the escapement lever 30 pivoted to the said cam lever permits the escapement wheel 28 to move notch by notch, said wheel being driven by the power stored 130

in the spring 29 by the rotation of the shaft 15, the cam wheel 32 and type wheel 18 pivoted thereto, also moving step by step with the escapement wheel 28. As the cam pawl 33 traverses the contour of the cam wheel 32, the bar 35 is raised, and the pin carried by the projection 36 upon the plate 35 traverses the slot formed in the free end of the plate 37, retracting the ratchet actuating pawl 38 carried by said plate, said pawl engaging the next tooth upon the ratchet wheel 29. When the type wheel 18 has made a complete revolution, the pawl 38 is forced into the position shown in Fig. 6 by the power stored in the spring 34 by the outward movement of said pawl, the pin carried by the projection 36 upon the bar or rod 35 forcing the plate 37 again into normal position and advancing the ratchet actuating pawl 38 which rotates the ratchet wheel 39 one notch and brings the next character upon the type wheel 19 attached thereto, into printing position.

A cam wheel 40 is pivoted to the ratchet wheel 39 and adapted to be engaged by a pawl 41 pivoted to the stationary shaft 16, and held in engagement with the cam wheel by the small spring 42 carried by the plate 17. Formed integral with the cam pawl 41 and also pivoted to the stationary shaft 16 is a finger or projection 43 carrying a pin 44 adapted to engage a slot 45 formed in the free end of a plate 46; the other end of said plate being loosely mounted upon the shaft 15, as shown in Fig. 5. A ratchet actuating pawl or finger 47 is pivoted to the plate 46 and adapted to actuate the ratchet wheel 48 pivoted to the type wheel 20. The ratchet actuating finger 47 is held in engagement with the ratchet wheel 48 by a small spring 49.

The cam wheel 40 pivoted to the type wheel 19 has two curved faces, as shown in Fig. 5. As the pawl 41 is raised by the cam faces of the wheel 40, the pin 44 carried by the projection or arm 43 integrally connected with the pawl 41 moves radially with reference to the stationary shaft 16; said pin moves the plate 46 and the ratchet actuating pawl 47 attached thereto, by means of the slot 45 formed in said plate, radially with reference to the shaft 15, thus retracting the ratchet pawl 47 upon the ratchet wheel 48 until said pawl engages the next notch carried by said wheel; the ratchet wheel 48 being advanced one notch when the pawl 41 drops from the cam face of the wheel 40 to the position shown in Fig. 5. It will thus be seen that when the type wheel 19 to which is pivoted the cam wheel 40, has made one-half a revolution, the type wheel 20 to which is pivoted the ratchet wheel 48, is advanced one notch and the next character upon said wheel is brought into printing position. A cam wheel 50 is piv-

oted to the type wheel 19 and adapted to be engaged by a cam riding pawl 51, pivoted to the stationary frame 16, and held in engagement therewith by the spring 54. Formed integral with the cam pawl 51 is a rod or bar 52, as shown in Fig. 9, said bar being connected to a projection or finger 53, pivoted to the stationary frame 16. A small pin is carried by the projecting finger 53 adapted to engage a slot formed in the plate 55, the opposite end of said plate being pivoted to the shaft 15, said plate carrying a ratchet actuating pawl adapted to engage the periphery of the ratchet wheel 56 pivoted to the type wheel 21 and adapted to rotate the wheel 21 one notch for every revolution of the type wheel 19, by means of the bar 52 integrally connected with the pawl 51 and the projection 53 movably attached to the plate 55.

A cam wheel 57 is pivoted to the type wheel 21 and adapted to be engaged by a cam riding pawl 58 pivoted to the stationary shaft 16, said pawl carrying a pin 59 adapted to reciprocate within the slot 60 formed in the free end of the plate 60, said plate being loosely pivoted to the shaft 15 and carrying a ratchet actuating pawl or finger 61 adapted to rotate the ratchet wheel 62 pivoted to the type wheel 22. A cam wheel 63 is pivoted to the type wheel 22 and adapted to be engaged by a cam riding pawl 64 pivoted to the stationary frame 16. Integrally connected with the pawl 64 is a projection or finger 65 carrying a pin 66, said pin being adapted to reciprocate in a slot formed in the free end of the plate 67, said plate being pivoted to the shaft 15, and carrying the ratchet actuating finger or pawl 68, said pawl finger being adapted to engage the periphery of the ratchet wheel 69 and rotate said ratchet wheel step by step, thus bringing the characters carried by the type wheel 23, to which the ratchet wheel 69 is pivoted, successively into printing position.

Carried by the stationary shaft 16 are dead pawls 70, 70, adapted to engage the ratchet wheels 39, 48, 56, 62 and 69, said dead pawls 70 being held in engagement therewith by small springs 71 carried by the bar or plate 17, and being adapted to hold said wheels against back lash.

The operations of the cam riding and ratchet actuating pawls and the co-acting movable plates and ratchet actuating fingers carried by said plates, are all substantially as described with reference to Fig. 5.

The type wheels may be formed of metal or of resilient material, as desired, the resilient material being adapted to conform to irregularities in the surface of the article to be stamped.

While I have described the construction and operation of means for relatively and intermittently rotating the type wheels,

obvious that many changes may be made in the arrangements and detail construction of said means.

- The teeth or leaves carried by the pinions 7 and 24 are adapted to mesh when the printing mechanism is returned by the spring 14, after an impression has been made, and move the impression mechanism slightly to compensate for the movement of the motor mechanism during the time the impression mechanism has been disconnected from the motor mechanism, thus synchronizing the impression mechanism with the motor.
15. A stop 72, preferably having two projecting points is carried by the plate or rod 17, said points being adapted to engage radially disposed grooves or notches (not shown) formed upon the inner face of the pinion 24, 20 said plate or strip 72 permitting the impression mechanism to rotate when in engagement with the motor, but constituting a brake or lock upon the impression mechanism, and being adapted to prevent any inadvertent rotation of the type wheels when the impression mechanism is disconnected from the motor mechanism.

The year and month 73 not having to be changed often, I preferably mount the same 30 stationarily upon the extended end 11 of the actuating rod 9.

Loosely pivoted on a shaft 74 between the supporting rod 11 and one end of the supporting frame 12, is a plurality of type 35 wheels 75, 75. Ratchet wheels 76, 76, are attached to each of said type wheels 75. Each of the type wheels 75 carries upon the periphery thereof the numerals 1, 2, 3, 4, 5, 6, 7, 8, 9, 0. A frame 77 secured to the support 11 and the shaft 74 extends around said type wheels and has pivoted thereto a rod 78, said rod carrying a plurality of dead pawls 79, 79. One of said dead pawls is adapted to engage each of the ratchet 45 wheels 76 to prevent back lash of said wheels, springs 80, 80, holding said dead pawls in engagement with their respective ratchet wheels. A pawl frame 81 extends around the type wheels 75, 75, and is loosely pivoted 50 to the shaft 74, said frame 81 carrying a plurality of ratchet actuating pawls 82, 82, said pawls being of different lengths, as shown in Figs. 7 and 9. A coiled spring 89 carried by a rod supported by said pawl frame is adapted to hold the pawls 82, 82 in engagement with their respective ratchet wheels. Each of the ratchet wheels 76 has a cut out portion 83 formed therein, said ratchet wheels being disposed to bring the 60 cut out portions 83, 83, in alinement. A plate 84 having a longitudinal slot 85 is pivoted to the movable supporting frame 12 in any suitable manner, as by the pin 86. A pin 87 carried by the stationary frame 3 65 being adapted to reciprocate within the slot

85. Attached to the pawl frame 81 is a link 88 which is pivoted at one end to the pawl frame 81, the other end of said link being pivoted to the plate 84.

The operation of the numbering device is 70 as follows: When the movable supporting frame 12 is depressed, the pin 87 carried by the stationary frame 3 traverses the slot 85 and carries the end of the link 88 pivoted to the plate 84 radially with reference to the 75 pin 86 carried by the movable frame 12, as shown in Fig. 8, the link 88 retracting the cam frame 81, the pawls 82 also being retracted, and the pawl 82 then in engagement with a ratchet wheel 75 engaging the 80 next notch thereon and rotating said ratchet wheel when the movable frame 81 is returned to its normal position by the spring 14 carried upon the rod 9.

After the first type wheel 75 upon the 85 right, has made one revolution, the pawl 82 adapted to actuate the ratchet wheel pivoted to said type wheel, drops into the aperture 83 formed in said ratchet wheel and the next pawl 82 from the right engages its 90 ratchet wheel, the two type wheels upon the right rotating together one notch. It will be seen that the pawls 82 being of different lengths are held out of engagement with their respective ratchet wheels, excepting 95 when the longer pawls drop into the apertures 83 formed in the ratchet wheels.

The construction and operation of the type and ratchet wheels, of the numbering device above described, and their respective 100 pawls will be readily understood by those familiar with this art, as the arrangement and operation of the wheels and their actuating pawls is of the type familiarly used in automatic numbering devices.

An inking pad 90 is adapted to ink the operative faces of the type wheels, said pad being adapted to rest normally out of engagement with said type wheels and being pivoted to the stationary frame 3, as shown 110 in Fig. 7. Carried by the support 11 is an arm 91 carrying a roller 92, said roller being adapted to engage the pad 90, when an impression is made, the pad being carried from the path of the impression mechanism as 115 shown in Fig. 8. A spring 93 is adapted to return the pad 90 to its normal position. The pad 90 is adapted to be first engaged by the operative faces of the type wheels, and after inking said type wheels, to be engaged 120 by the roller 92 carried by the support 91, said roller traversing the pad 90 transversely and carrying said pad out of the path of the impression mechanism, as shown in Fig. 8.

Having described my invention what I 125 claim as new and desire to secure by Letters Patent is:

1. The combination in a stamp, of a reciprocating frame, time printing means carried thereby, a motor for automatically varying 130

the character of the impression made by said means, number printing means carried by the reciprocating frame, and automatic means for varying the character of the impression made thereby.

2. The combination in a stamp, of a reciprocating frame, time printing means carried thereby, a motor for automatically varying the character of the impression made thereby, number printing means carried by the reciprocating frame, and means operated by the making of an impression for automatically varying the character of the impression made by said number printing means.

3. The combination in a stamp, of a reciprocating frame, time printing means carried thereby, a motor for automatically varying the character of the impression made thereby, number printing means carried by the reciprocating frame, means operated by the impression movement of the stamp for automatically varying the character of the impression made by said number printing means, and means for automatically inking said time and number printing means.

4. The combination in a stamp, of a reciprocating frame, time printing means carried thereby, a motor for automatically varying the character of the impression made thereby, number printing means carried by the reciprocating frame, means for automatically varying the character of the impression made thereby, and pads normally out of engagement with said time and number printing means for automatically inking the same between successive operations of the stamp.

5. The combination in a stamp, of a reciprocating frame, a motor, movable time printing means carried by said reciprocating frame operated by said motor and separable therefrom in making an impression, number printing means carried by said reciprocating frame and movable with said time printing means, and means operated by the impression movement for automatically varying the character of the impression made by said number printing means.

6. The combination in a stamp, of a reciprocating frame, a motor, movable time printing means carried by said reciprocating frame operated by said motor and separable therefrom in making an impression, number printing means carried by said reciprocating frame and movable with said time printing

means, means operated by the impression movement for automatically varying the character of the impression made by said number printing means, and means for automatically inking said time and number printing means.

7. The combination in a stamp, of a stationary frame, a motor mounted on said frame, a reciprocating frame, time printing means mounted on said reciprocating frame operated by said motor and separable therefrom in making an impression, number printing means mounted on said reciprocating frame, and means operated by the impression movement for automatically varying the character of the impression made by said number printing means.

8. The combination in a stamp, of a stationary frame, a motor mounted thereon, a reciprocating frame, time printing means carried by said reciprocating frame operated by said motor and separable therefrom in making an impression, number printing means mounted on said reciprocating frame, means operated by the impression movement for automatically varying the character of the impression made by said number printing means, and means for automatically inking said number and time printing impression means.

9. The combination in a stamp, of a stationary frame having gage parts for engaging the surface to be impressed, a motor mounted on said frame, a frame reciprocating between said gage parts, time printing means carried by said reciprocating frame operated by said motor and separable therefrom in making an impression, number printing means carried by said reciprocating frame, means operated by the movement of said reciprocating frame for automatically varying the impression made by said number printing means, and a pad normally out of engagement with said time and number printing means for automatically inking the same before each impression.

In witness whereof, I have hereunto subscribed my name in the presence of two witnesses.

FREDERICK PURDY.
